MERCHANTISE SHIPPING AND DISPLAY
PACKAGE

Nicholas Snelling, Jackson Heights, N. Y., assignor
to The National Process Company, New York,
N. Y., a corporation of New York

Application July 21, 1937, Serial No. 154,714

3 Claims. (CL. 206—44)

This invention relates to the packing and displaying of merchandise and particularly to a combination package of this class wherein the container proper is of irregular contour and in a display arrangement with the articles supported therein in display position, and outer filling and reinforcing box elements are employed in connection with the container in forming a shipping package of substantially smooth contour throughout, and the object of the invention is to provide a combination package of the character described wherein the container proper may be composed of very light-weight and inexpensive material to materially reduce the cost of manufacturing the same, whereas the outer filler and enclosing parts of the package are constructed of inexpensive reinforcing material; a further object being to provide a container of the character described which is formed from a single piece of material folded to form storage sections and display sections of irregular contour, and wherein the outer box part or wrapper is fashioned to form foldable box-like sections forming fillers in the irregular contour of the container and in converting the resulting package into an even rectangular form, the greatest dimensions of which are governed substantially by the greatest dimension of said container, and with these and other objects in view, the invention consists in a package of the class and for the purpose specified which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a perspective view of one form of container made according to my invention illustrating the outer wrapper thereof in partially assembled position with respect to the container.

Fig. 2 is a vertical section through the device shown in Fig. 1 in completely assembled position.

Fig. 3 is a plan view of the blank from which the container shown in Figs. 1 and 2 is formed.

Fig. 4 is a view similar to Fig. 1 showing a modified form of construction.

Fig. 5 is a partial section on the line 5—5 of Fig. 4 showing the container detached.

Fig. 6 is a plan view of a blank from which the container shown in Fig. 4 is formed.

Fig. 7 is a perspective view of another form of

container which I employ omitting the outer wrapper therefor.

Fig. 8 is a vertical section of the container shown in Fig. 7 illustrating one method of applying a wrapper thereon.

Fig. 9 is a sectional detail view showing a part of the container illustrated in Fig. 7 in folded position to illustrate another method of packing the same, and

Fig. 10 is a plan view of a blank from which the device shown in Figs. 7, 8, and 9, is formed.

In carrying my invention into effect, I construct a container proper in such manner as to form a complete display package thereof, with 15 the articles of merchandise arranged therein so that when the outer filler and reinforcing parts of a complete shipping package are removed, the container is ready to be placed upon a shelf, counter, or other support to display the merchandise therein without the necessity of the merchant opening or otherwise tampering with the resulting package or container, thus assuring the manufacturer of the proper arrangement of his display when used by the merchant, as well 20 as eliminating the loss of time which has, heretofore, been necessary in setting up combination display containers of conventional construction.

In addition to the forming, and by reason of the use of the heavy reinforcing outer package parts, the inner container proper may be composed of lightweight material which in itself would not be suitable for the shipment of the merchandise, but which on the other hand is sufficient to sustain the articles of merchandise in a displayed manner. In other words, my invention provides a material saving in the cost of a complete display package of the character described which will run into considerable savings to a manufacturer in the packing and shipment of merchandise.

In the accompanying drawings I have shown a few adaptations of my invention, and in Figs. 1 to 3 inclusive, I have shown a container 11 formed from a blank similar to that shown in Fig. 3 and consisting of a front wall part 12, side wall parts 13, 13a, a supplemental front wall part 14 adapted to extend forwardly of the wall part 12 by reason of the folded coupling section 15, a bottom wall part 16 foldable with respect to the lower edge of the part 14, a supplemental bottom 45 16a including a flap portion 16b, the latter being glued or otherwise secured to the bottom 16. The lower ends of the side walls 13a are provided with flaps 17, 17a which are adapted to be arranged 50 between the walls 16, 16a when the container is

assembled and may be secured in this position if desired. The rear edges of the walls 13, 13a are provided with inwardly foldable back wall flanges 18, 18a which aid in supporting articles of merchandise 19, such for example, as cakes of soap against accidental displacement from the container, while at the same time permitting free removal of such articles from the rear of the container.

It will be noted upon a consideration of Fig. 2 of the drawings that part of the cakes of soap, or other merchandise, is arranged horizontally to extend into the forwardly projecting bottom portion of the container, whereas the other articles are disposed vertically at the rear of the wall 12, and in the construction shown, extend to a point below the top of said wall so as to form a chamber or compartment above the articles 19 rearwardly of the wall 12. In some instances the wall 14 may have an upwardly extending display part 14a formed from the part 15 and the wall 14 as well as the walls 12, 13, 13a, and if desired the wall 15 may be printed, lithographed, or otherwise characterized to produce an attractive display package. This package is entirely open at the back except for the flanges 18, 18a. It will thus be seen that the container thus formed is not suitable, in itself, for the shipment of merchandise.

I also employ supplemental container or packaging parts consisting of a combination cover and filler part 20 and an outer housing or sleeve part 21 both preferably composed of heavy or strong durable material, such for example, as corrugated board. The parts 20 and 21 may be economically cut from strips of corrugated board, the part 20 or the end portions thereof, being folded to form filler members 20, and 20b, the member 20a being adapted to be arranged upon the front wall 12 of the container and above the outwardly extending part 15, in the manner clearly illustrated in Fig. 2 of the drawings, whereas the member 20b is disposed at the rear of the wall 12 and above the articles 19.

It will thus be seen that when the member 20 is assembled, a complete rectangular package is formed, which package is open at the sides only, and these sides are closed and the part 20 held in position by the enveloping sleeve 21, the end portions 21a of which are adapted to be overlapped and glued, tied, or otherwise secured together so that the remainder of the package, consisting of the container 11 and the part 20 may be moved through the part 21 in opening the package. A suitable sealing strip can be provided over the upper and lower ends of the package to prevent displacement of the parts in shipment if desired, or the entire package may be arranged in an outer paper or wrapper.

The construction shown in Figs. 4, 5, and 6, differs from that shown in Figs. 1 to 3 inclusive primarily in the formation of a more complete box at the lower end of the container 22. With this construction, the blank of which is shown in Fig. 6, the parts 23, 24, 24a, 25, 26 and 27, are substantially similar in arrangement but different in construction to the parts 12, 13, 13a, 14, 15, and 16. Substituted for the part 16a is a part 28 which in the construction shown, forms a back wall for the container 22, the wall having an inwardly foldable supplemental back wall 28a which is adapted to fold over overlapped ends of additional supplemental back walls 28b, 28c which are foldable with respect to the side walls 24, 24a, the walls 28b, 28c having upwardly ex-

tending tabs 29 which are adapted to register with a tab 29a formed at the upper edge of the back wall 28. The wall 28 also includes side wall parts 30, 30a terminating at their ends in flaps 31, 31a which are adapted to be arranged inwardly of the wall 25, the walls 30, 30a being arranged outwardly of the side walls 24, 24a. The lower edges of the side walls 24, 24a, include inwardly foldable bottom flanges 32, 32a and similar flanges 33, 33a are formed on the lower edges of the side walls 30, 30a.

The resulting container 22 shown in Figs. 4 to 6 inclusive is naturally of a more substantial and stronger construction than the container shown in Figs. 1 to 3. However the lightweight construction thereof, and due to the fact that all of the articles of merchandise are arranged in the lower portion of the container, means are necessary to reinforce and support the front display wall 23 and that part of the walls 24, 24a above the wall 26, which forms the top of the container proper. This result is accomplished by the use of a package part 34 similar to the part 20 and having a filler member 34a similar to the member 20a and a member 34b similar to the member 20b. It will be understood that an outer part similar to the part 21 will also be used in conjunction with the structure shown in Fig. 4, but this part is omitted simply for clarity.

In Figs. 7 to 10 inclusive, I have shown a further modification which modifies the structure shown in Figs. 4, 5, and 6 primarily in providing one container, the forward projection of which simply acts as a display and article support but does not support the articles of merchandise in the shipment and transportation thereof. With this construction the container 35 is formed from a blank similar to that shown in Fig. 10 having a front display wall 36 joining a bottom wall 37 in a foldable display and article supporting section 38 consisting of top wall parts 39, front wall parts 40 separated by a large opening 41 in which an article of merchandise taken from the container 35 may be placed in perpendicular display, the contour of the opening 41 conforming substantially with the contour of the article.

It will be understood that the forward end of the bottom wall 37 supports the walls 39 and 40 in extended position. However, these walls may be folded along a line 42 to collapse the walls 39, 40, including the extension of the bottom wall 37 upon the front wall 36 in the manner illustrated in Fig. 9 of the drawings, when the entire container is packed in the outer wrappers. On the other hand outer wrappings similar to that shown in Figs. 1 and 4 may be employed as is illustrated in Fig. 8.

The front wall 36 has foldable side walls 43, 43a having extending flaps 44, 44a adapted to extend into openings 45, formed between foldable back wall parts 46, 47. The bottom wall includes upwardly extending side wall parts 48, 48a each having foldable back wall parts 49, 49a which are adapted to be arranged within the parts 46, 47, the parts 49, 49a having projecting tabs 50 which are free to pass through the openings 45 the same as the rounded tab portions on the flaps 44, 44a.

The container 35 is adapted primarily for supporting tall packages which would extend upwardly above the bottom wall 37 to a position substantially similar to that indicated by the line x in Fig. 8 of the drawings, so that in applying an outer package part 51 to the container, the filler member 51a thereof will extend down to

the line α as indicated in Fig. 8 of the drawings. If the part 51 is to be arranged as in the manner shown in Fig. 8, the other end thereof will include a filler part 51b which is disposed over the walls 39 as will be apparent. Using the construction as seen in Fig. 9, the member 51b would of course be removed.

It will be understood that the illustrations in the accompanying drawings simply demonstrate a few forms or adaptations of my invention and it will be apparent that many variations or modifications may be made in the form and construction of the container proper to adapt it for the packing and displaying of merchandise especially in a manner to render the packed merchandise freely accessible from the rear of the container for delivery to a purchaser, while at the same time producing at the front and sides of the container the representation of a complete and substantially closed container.

It will also be understood that the filler members of the outer package parts may be shaped to conform with and snugly support the vacant or open portions of the container proper to prevent displacement of the merchandise in said containers in the shipment or transportation thereof. It will also be noted that the filler members are disposed on opposite sides of the display portion of the container so that this display portion regardless of its contour is reinforced and protected against damage during the shipment of the complete package.

It will be apparent that my invention adapts itself primarily for use in the packing, shipping, and displaying of relatively small articles of merchandise, such for example as bottled goods, small package goods, cakes of soap and the like, and is especially adaptable for use in the merchandising of drugs, cosmetics, and similar merchandise.

Having fully described my invention, what I claim as new and desire to secure by Letters Patent, is:

1. A merchandise shipping and display container comprising a unitary blank of sheet material die cut and scored to form foldably related wall parts, predetermined wall parts being adapted, in the assembled position of said container, to form integral bottom, front, and front platform portions of said container, said platform being horizontal and extending rearwardly from the top edge of the front wall, a supplemental front wall integral with the rear edge of said front platform and extending in permanent perpendicular position above said platform at a point intermediate the front wall and the rear of said container, side wall members integral with said supplemental front wall and extending to the bottom of said container, other foldable wall parts forming means for supporting and securing said container in the assembled position, and said container being adapted for the packing of merchandise throughout the entire volume thereof below said front platform as well as between the supplemental front wall and side walls extending above said platform.

65

2. A merchandise shipping and display container comprising a unitary blank of sheet material die cut and scored to form foldably related wall parts, predetermined wall parts being adapted, in the assembled position of said container, to form integral bottom, front, and front platform portions of said container, said platform being horizontal and extending rearwardly from the top edge of the front wall, a supplemental front wall integral with the rear edge of said front platform and extending in permanent perpendicular position above said platform at a point intermediate the front wall and the rear of said container, side wall members integral with said supplemental front wall and extending to the bottom of said container, other foldable wall parts forming means for supporting and securing said container in the assembled position, and said container being adapted for the packing of merchandise throughout the entire volume thereof below said front platform as well as between the supplemental front wall and side walls extending above said platform.
3. A merchandise shipping and display container comprising a unitary blank of sheet material die cut and scored to form foldably related wall parts, predetermined wall parts being adapted, in the assembled position of said container, to form integral bottom, front, and front platform portions of said container, said platform being horizontal and extending rearwardly from the top edge of the front wall, a supplemental front wall integral with the rear edge of said front platform and extending in permanent perpendicular position above said platform at a point intermediate the front wall and the rear of said container, side wall members integral with said supplemental front wall and extending to the bottom of said container, other foldable wall parts forming means for supporting and securing said container in the assembled position, and said container being adapted for the packing of merchandise throughout the entire volume thereof below said front platform as well as between the supplemental front wall and side walls extending above said platform.
4. A merchandise shipping and display container comprising a unitary blank of sheet material die cut and scored to form foldably related wall parts, predetermined wall parts being adapted, in the assembled position of said container, to form integral bottom, front, and front platform portions of said container, said platform being horizontal and extending rearwardly from the top edge of the front wall, a supplemental front wall integral with the rear edge of said front platform and extending in permanent perpendicular position above said platform at a point intermediate the front wall and the rear of said container, side wall members integral with said supplemental front wall and extending to the bottom of said container, other foldable wall parts forming means for supporting and securing said container in the assembled position, and said container being adapted for the packing of merchandise throughout the entire volume thereof below said front platform as well as between the supplemental front wall and side walls extending above said platform, the upper extremities of said side wall members terminating above the upper limits of the articles of merchandise to be arranged therebetween and below the upper extremity of said supplemental front wall, thereby forming of said supplemental front wall and side wall members effective display panels for substantially concealing the articles of merchandise therebetween, and said front platform being cut out to receive an article of merchandise supported in displayed position.

NICHOLAS SNELLING.
